UNITED STATES PATENT OFFICE

MARC A. MIGNEY, OF ROCHESTER, NEW YORK, ASSIGNOR TO METAL ARTS CO. INC., OF ROCHESTER, NEW YORK

DESIGN FOR A PERPETUAL CALENDAR

Application filed August 22, 1932. Serial No. 44,659. Term of patent 3½ years.

To all whom it may concern:

Be it known that I, MARC A. MIGNEY, a citizen of the United States, residing at Rochester, in the county of Monroe and State of New York, have invented a new, original, and ornamental Design for a Perpetual Calendar, of which the following is a specification, reference being had to the accompanying drawing, forming a part thereof.

Figure 1 is a front elevation of the perpetual calendar, showing my new design.

Figure 2 is a top plan view of the same.

Figure 3 is a perspective view of the same.

I claim:

The ornamental design for a perpetual calendar, as shown.

MARC A. MIGNEY.
